UNITED STATES PATENT OFFICE.

RHODA M. ROESSNER, OF NEW YORK, N. Y.

PUZZLE.

No. 868,702.

Specification of Letters Patent.

Patented Oct. 22, 1907.

Application filed October 29, 1906. Serial No. 341,032.

To all whom it may concern:

Be it known that I, RHODA M. ROESSNER, a citizen of the United States, residing in the borough of Bronx, city, county, and State of New York, have invented 5 certain new and useful Improvements in Puzzles, of which the following is a specification.

My improvements relate to the class of obstacle puzzles in which the solution consists in detaching one article from another without severing the connecting 10 cord.

The invention consists in the specific construction and arrangement of parts hereinafter described and claimed.

In the accompanying drawings, Figure 1, is an elevation of my improved puzzle; Fig. 2, is an elevation of the reverse side of the perforated plate, also illustrating the manipulation and solution of the lower portion of the puzzle.

P, is a perforated plate of any desired configuration 20 and made of any suitable material, preferably though not necessarily stiff, formed with the series of holes 1, 2, 3, 4, 5, 6 and 7.

B is a bead or equivalent article strung upon the doubled portion of the endless cord C which is inter- 25 laced around and through the plate P as shown in the drawings.

Strung upon the opposite or free portion of the endless cord C is a ring or similar object of flexible material. One or more of these objects F may be used as 30 preferred and they may be of any desired shape or configuration provided they have a relatively large central opening f, and relatively narrow continuous rims f'. I prefer to use two of these flexible objects F as shown in the drawings, in the form of rings through 35 which is looped the central portion of a string or flexible cord S, to the end of which are attached rigid symbolic objects A, A, of greater size than the internal diameter of the ring R, through which the ends of the string S have been passed prior to the attachment of the 40 rigid objects A, A.

The assembling of the perforated flexible rings or like objects F on the string S, ring R and rigid objects A, will be clearly understood from the above. The other parts may be assembled before the ends of the 45 endless cord C are united. Thus, bring the ununiting ends of the cord C together and pass them through the hole 1 from the front of the plate P leaving the extremity c, of the loop on the front side of the plate where it may be held temporarily by hand. Next pass the ends 50 of the cord C through the opening 2 to the front of the plate, over the latter and return to the back of the plate P through the hole 3; thence over the back of the plate to and through hole 4 to the front of the plate; thence (first passing bead or equivalent object 55 B over loop c) pass the ends of the cord C through its

loop c, and then through hole 5 to the back of the plate, down the same to and through the hole 6 and over the face of the plate to and through hole 7 after which the ends are separated, passed through the flexible rings F and united to form the endless cord C. 60

It is to be understood in this connection that I herein use the words "cord" and "string" to designate any suitable flexible equivalent thereof, as a wire, fine chain, or the like.

The object of the puzzle is two-fold. First, to release the rigid objects A, A, from the ring R and flexible perforated objects F, F, without cutting the string S or severing the other parts; and secondarily, to release the bead or equivalent B without severing the endless cord C. The first solution is attained by doubling the flexible objects F and passing them through the ring R as indicated in Fig. 2, after which the rigid objects may be readily passed through and freed from said flexible objects F. 65

The second solution is attained as follows: First 70 draw up the cord through the several holes so as to afford sufficient slackness behind the loop c, to admit of manipulation, then pass the loop c, through the hole 5 to the rear of the plate, then return to front of plate through hole 6, then back through hole 7 when the 80 loop c, may be passed over the objects F (and the string S, ring R and rigid objects A is still attached to the flexible objects F) and withdrawn through holes 7, 6, and 5, when the bead or equivalent B may be withdrawn. By reversing this process of manipulation 85 with relation to each other, so that the puzzle may be used repeatedly.

What I claim as my invention and desire to secure 90 by Letters Patent is,

1. In a puzzle of the character designated, the combination with a flexible object formed with a relatively large aperture and narrow continuous rim, of a flexible cord or equivalent passing through said flexible object and through a ring of relatively small diameter, said ring, and rigid objects attached to said flexible cord, of greater width than the internal diameter of said ring, for the purpose described. 95

2. In a puzzle of the character designated, the combination of a flexible object formed with a relatively large aperture and narrow continuous rim, a flexible cord or equivalent passing through said flexible object and through a ring of relatively small diameter, said ring, rigid objects attached to said flexible cord of greater width than the internal diameter of said ring, an endless cord passing through 100 a loop formed in itself and through said flexible object and laced through a series of holes in a plate, said perforated plate, and a bead or equivalent object strung upon the loop in the endless cord, for the purpose described. 105
